METHOD OF AND APPARATUS FOR THE FORMATION OF CONCRETE PIPES

Nelson E. Gowing, Wombourne,
Wolverhampton, EnglandApplication July 22, 1949, Serial No. 106,166
In Great Britain December 24, 1948

17 Claims. (Cl. 25—36)

1

This invention relates to a process and apparatus for the formation of concrete pipes by moulding, and relates to that type of process wherein the pipe is formed from concrete of a stiff consistency (for example having a minimum consistency factor of 250 as recorded on the Wigmore Consistometer) within a vertical mould by utilising a rotary piston or packer having packer elements, the said piston moving vertically upwardly from the bottom of the mould whilst rotating, with the concrete mix fed on to its head, the centrifugal force throwing the concrete mix outwardly, so that a shell is built up against the mould which is consolidated by the rotating piston.

The apparatus or machine utilised for carrying out the above process is of the type consisting of a suitable supporting structure or framework having means for holding the mould and locating same in axial alignment with the piston, the piston being carried and rotated by a vertical shaft, the apparatus including means for moving said shaft axially, i. e. up and down, whereby the piston during the pipe forming operation traverses within the mould from the bottom to the top, the piston, its shaft and parts moving therewith being counterbalanced. The pipe or shell is formed by pouring the concrete on to the top or head of the piston, the centrifugal force throwing the mix outwardly where it is built up into a shell and consolidated by the piston and packer elements, and after formation when the piston and shaft are clear of the mould the said mould is removed from the apparatus, with the formed and "green" pipe therein.

With the process above set out, the consolidating action of the piston when forming the pipe results in liquid or "fat" forming on the inner wall or bore, and this formation, coupled with the helical path of travel of the piston, causes ridges or irregularities to form on the said wall. It is customary for pipes manufactured by this process to be finished off as well as possible by means of smoothing or pallet knives immediately after pipe formation when the mould has been removed from the machine, but even with this finishing, it is difficult to produce a perfectly even or unscored bore, or a pipe of the standard normally associated with pipes manufactured by the centrifugal spinning process. This latter process however cannot produce pipes so cheaply as they can be produced by a moulding process of the above type.

The primary object of the present invention is to provide an improved process and apparatus for the formation of concrete pipes by moulding

2

wherein the bore of the pipe, after the formation of said pipe, is smoothed mechanically and adequately, the smoothing action taking place whilst the mould is still in its position in the pipe-forming machine.

A further object of the invention is to provide an improved process and apparatus for the formation of concrete pipes wherein the inner wall can be lined with a suitable material which enables extremely smooth and if necessary, substantially impervious pipes to be made as compared with pipes manufactured by normal moulding methods, thus producing a moulded pipe that is adequately consolidated and which will pass 15 the standard accepted air pressure test.

Another object is to provide a process and apparatus which will enable smooth bore pipes to be manufactured at a cost which compares favourably with pipes as at present produced by 20 existing moulding apparatus.

A further object is to provide an apparatus which is easily-operated and of robust construction.

Yet another object of the invention is to provide 25 an apparatus which can be utilised for the production within limits of pipes of various lengths and diameters, whilst a further object is to provide an apparatus in which metal or other reinforcement can be set up in the mould to be 30 embedded within the formed shell.

In order that a clear understanding of the invention may be obtained a preferred form of 35 machine for forming pipes in accordance with the invention will now be described with reference to the accompanying drawing in which:

Figure 1 is a front view of the machine with the piston at its lowest point of travel;

Figure 2 is a side view of Fig. 1;

Figure 3 is a plan view showing the mechanism

40 for driving the piston vertically;

Figure 4 is a plan view to an enlarged scale of the piston;

Figure 5 is a side view of the piston partly in section, and

45 Figure 6 is a plan view of the turntable and its supporting tray.

Referring to the drawings, the framework 50 consists of suitable uprights and cross bracing members of H-, angle section or like strip indicated generally by the reference numeral 10. The main supporting member for the assembly consisting of the piston 11, its shaft 12 and its driving motor 13, consists of a vertical pillar 14 which is disposed centrally of the frame and is 55 of H-cross section. The said assembly is sup-

ported to move vertically and includes the electric motor 13 at the rear of the pillar 14, and a mounting 15 for the lower end of the piston shaft 12 and its outer casing 12a at the front of said pillar both carried on a suitable supporting structure 16, the motor driving the shaft through pulley and belt drive indicated generally 17. The supporting structure has rollers 18 which run on suitable vertical parts of the frame, the whole structure being mounted in such a way that side to side movement is absent or reduced to a minimum.

The piston 11 is mounted on the upper end of the shaft, which shaft is of such a length that it can traverse vertically the length of the appropriate mould. It will be noted that the piston is on the top of its shaft, in contradistinction to the usual arrangement in which the piston is carried at the bottom of its shaft, and it is a feature of the invention that the piston is rigidly supported. Thus, the shaft is carried within the outer sleeve 12a the outer diameter of which need be but little less than the diameter of the piston.

The drive for moving the piston and motor assembly is mounted on the top of the frame. This drive consists essentially of an electric motor 19, the direction of rotation of which can be reversed by a suitable switch, said motor driving through a change speed gearing a cross-shaft 20 each end of which carries a flanged drum 21 around which is a cable 22 (one at each side of the frame) connected to the assembly. A counterbalance weight 23 running in a vertical guide 23a is provided at each side and the cable at each side extends from the weight over and around the drum 21 on the cross-shaft end down to a suitable part of the assembly where it is anchored. This is shown clearly in Fig. 2. With this arrangement overdrive is prevented as either the counterbalance weights or the piston assembly will rest on the ground or bottom members of the frame when the limit of movement is reached in either direction thereby loosening the cables around their shaft pulleys.

The motor 19 drives through sprockets 24, 25 and chain 26 a lay shaft 27 mounted in suitable journals across the top of the frame and near to the front, said shaft having two sprockets 28, 29, which sprockets drive through chains 30, 31, respectively sprockets 32, 33 free on the cross-shaft 20 at the rear of the lay shaft 27. A sliding dog member 34 is keyed on to the said cross-shaft between the two sprockets thereon, which member is toothed at each end whilst the facing bosses 35, 36, of the sprockets 32, 33, respectively are similarly formed so that a sliding dog clutch arrangement is provided. When the dog member 34 is moved along the shaft to engage the dogs of one of the sprockets 32, 33, the gear ratio between the motor and cross-shaft is different from the ratio when the dog member 34 is moved to engage the dogs of the other of said sprockets.

The change speed is conveniently effected automatically upon the reversal of the direction of rotation of the motor. Carried on and driven by one end of the lay shaft 27 is one element 37 of a friction drive, the other element 38 being co-axial therewith and pressed thereto by a spring 39. The second element 38 is coupled by an arm 40 the head of which is formed as a collar 41 on the shaft and between the element and linkage 42 to the dog member, and the arrangement is such that when the direction of

motor rotation is reversed the friction between the members results in the collar 41 turning through an angle sufficient to rock the arm 40 causing the dog member to slide on its shaft and engage the other sprocket. The ratio between the drive for the downward movement of the piston assembly and the upward movement thereof is preferably 3-1 so that the downward rate of travel of the piston is three times the upward rate.

The mould support consists of a lower or floor plate 43 having pins 44 for location in dowel holes in the bottom ring of a conventional two part mould shell, and an upper supporting tray 15 45 with a mould retaining ring 46 on its underside, said tray being mounted so as to be capable of vertical movement to allow for the insertion and removal of a mould and also if necessary, the utilisation of moulds of different heights. A circular plate 47 is mounted for rotation on the tray and also to serve as the support for an upper former as later described. The upper supporting tray is guided at each side by vertical members 48 which run on the vertical front members 25 of the supporting frame 10. Counterbalanced bars 59, 59, mounted on a cross axle 49 are connected by the coupling rods, 50, 50, to the underside of the tray 45. The cranked lever 51 projects from the front of the machine and is operatively connected to the axle 49, whereby on raising the lever the tray is raised through the rods 58 and bars 59, and on lowering the lever the tray is lowered. The arrangement is such that the tray tends to rise. The tray 45 has a central hole 52 with the mould locating means 46 on its underside.

Suitable stops are provided to retain the tray against upward movement during the pipe forming operation. Said stops comprise a pair of bars 53 one at each side actuated by a lever 54 connected to a counterbalanced arm 55 at one side of the machine, which arm is secured to a cross axle 56, said axle having connecting rods 57, 57, and links 58, 58, one at each side, the links being pivoted one to each bar 53. When the lever 54 is pushed inwardly the stops 53 are swung rearwardly about their upper pivots, thereby enabling the tray to rise and so allow for the insertion or removal of the mould. Conveniently each stop bar 53 is in two parts coupled together by a nut and bolt and slots, whereby the overall length can be adjusted.

The piston is illustrated in Figs. 4 and 5, and consists of a main body 11 having a central hollow boss 60, the lower edge of the skirt of which body is chamfered as at 61. The wall is preferably built up from metal strip 62 which has high wear resisting properties. A pair of packing elements 63, 63, are mounted on the piston crown. Each said element consists of a blade pivoted on a vertical pivot axle or spindle 64, the lower end of each axle being received in a recess 64a whilst the upper end of each spindle is received in a recess 64b, in a horizontal cross bar 66 mounted parallel with and in spaced relation to the piston head by the rods and spacers 87. The outer surfaces of the blades are vertical and the upper surfaces of the blades slope downwardly from front (with respect of the direction of travel, shown by the arrow in Fig. 4) to rear, and the said blades are coupled together through a toggle mechanism and a vertical actuating rod 65 passing through the centre of the piston and its driving shaft and freely rotatable with respect thereto. The upstanding

5

part of the rod 65 is formed as a plate 66 and on each side a bar 67 is pivoted, each bar 67 being connected at its outer end by a rigid curved rod 68, to a blade adjacent the pivot spindle of said blade. As shown in Fig. 1 the lower end of the actuating rod 65 projects from the lower end of the piston driving shaft and is supported through a suitable bearing at this end. A yoke 69 connects a collar 70 around the end of said rod to a lever 71 pivoted at 72 so that the depression of the lever end raises the actuating rod (which rod is free to turn) whilst the raising of said lever end lowers the actuating rod. The lever end is arranged to engage adjustable stops the one 73 at the limit of downward movement of the piston, the other 74 at the limit of upward movement.

When the piston is rising after the lever 71 has contacted the stop 73, the packer blades 63, 63, by their rear edges, overhang the piston wall an appropriate amount, e. g. about one eighth part of an inch. The two bars 67 aforesaid are aligned or past centre, toggle fashion in this position but when the piston reaches its limit of upward travel, the lever end meets the stop 74 thereby raising the actuating rod 65. Owing to the toggle linkage this results in the turning of the rod through a small angle and the packer elements or blades through the bars 67 and the curved rods 68, turn on their pivot spindle 64 an amount sufficient to bring their rear edges within the diameter of the piston. When the piston is at its limit of downward travel, the actuating rod is lowered thereby turning the blades to their projecting position.

The socket end of the pipe is formed at the top, the lower part of the mould having a ring or other suitable member therein to form the male end of the pipe. The plate 47 is if necessary, arranged to receive therein a cylindrical former the outer surface of which will decide the shape of the inner wall of the pipe at the mouth, the mix being forced between the former and the mould when the piston nears the top of its travel. Any suitable form of socket may be utilised and the former is not illustrated in the drawings. It is preferred however, to effect rotation of the socket former in a contrary direction to the direction of rotation of the piston and for this purpose, the plate 47 is mounted as a turntable having a channel section circumferential wall 75 supported by suitable rollers 76. The former is engaged in the turntable for example by means of projecting bars on the former which engage under lugs 83 on the plate 47, and the turntable is driven by an electric motor 77 beneath the table, the drive being through a telescopic shaft 78 and roller 79 mounted eccentrically. The said roller 79 is controlled by the hand lever 80, through linkage 81 beneath the table, whereby the roller can be brought to engage the wall 75, or drawn therefrom, a thrust roller 82 being provided. It will be understood that if it is necessary to rotate the plate 47, such rotation is necessary only when the piston approaches the plate. The turntable is prevented from movement in the same direction as the piston by means of the radial rack bars 84 and pawl 85.

As stated above the shape of the former will depend upon the required shape of the mouth and preferably, for forming a spigot and socket pipe, the machine employs a former and the apparatus as described in our co-pending application Serial No. 106,167 filed July 22, 1949.

It will be understood that for forming the

6

pipe, with the mould in position and the piston at its lowermost position, the drive to rotate the piston is started up (a speed of between 200 and 300 R. P. M. being suitable), and the mix is fed into the mould, the drive for raising the piston being started. The mix due to centrifugal force is flung outwardly against the mould. The packer blades by their rear parts overhang the piston slightly, and their height is such that the concrete is built up into a shell in the mould to be consolidated by the following piston. When the piston approaches the former member at the top, said member is rotated in the direction opposite to the direction of rotation of the piston. The piston will finally leave the mould and former and when the head is clear of the former, the packer blades are automatically retracted.

The direction of rotation of the motor assembly drive is now reversed and it returns at a faster axial speed through the pipe. This return movement causes the inner pipe surface to be smoothed and the tapering skirt of the piston assists in this operation.

If it is desired to line a pipe, after the return movement, the process is repeated and a suitable lining composition is fed on to the top of the piston. This composition may consist of sand and cement with or without other fillers such as powdered glass, carbon or other suitable material.

It will be understood that after lining, the piston must be returned, the return movement finishing off and smoothing the lined bore.

The second or lining operation, with the throwing on to the piston crown of the lining material, results in the packer blades wiping the material into the surface and also further compressing the concrete. In this way, an extremely hard inner surface can be obtained. It will be understood that the aggregate used in the mix includes a large proportion of fairly large stone chips, which tend to produce a rough and badly pitted inner surface. The lining operation in particular produces an inner surface in which there are no large cavities, and further the lining material can be selected so that the pipe is for all normal uses, impervious.

It is a further feature of the invention that metal reinforcement can be set up in the mould, as the packer blades do not overhang for the full mould diameter.

It will be seen that the smoothing operation is effected whilst the formed pipe is still in its mould which is in position in the machine, the piston, with its packer blades retracted being passed through the formed shell at the completion of the forming operation. As no substantial consolidation of the concrete is necessary, the axial speed is greater during smoothing than during forming, and said speed must be such that no undue burning of the bore or lining takes place.

Whilst a preferred mode of and apparatus for carrying the invention into effect has been described and illustrated, it is to be understood that alterations or modifications may be made without departing from the spirit of the invention as claimed in the appended claims.

I claim:

1. A process of forming concrete pipes by moulding and involving the use of a vertical mould within which a co-axial vertically moving rotating piston travels, said piston being mounted on the upper end of its driving shaft and having packing blades at its top which project beyond the piston wall, said process consisting in moving the rotating piston from the bottom of the mould

to the top whilst the concrete mix is poured on to the head of the piston, there to be flung outwardly and formed and consolidated into the pipe shell by the packer blades and piston, retracting said blades after the shell formation to within the diameter of the piston, and returning the said piston at a speed higher than the speed of the upward moving piston with the blades retracted through the formed shell, the speed of travel on the return being such that the piston serves to smooth and clean up the inner wall, without burning.

2. A process of forming concrete pipes by moulding and involving the use of a vertical mould within which a co-axial vertically moving rotating piston travels, said piston being mounted on the upper end of its driving shaft and having packing blades at its top which project beyond the piston wall, said process consisting in moving the rotating piston from the bottom of the mould to the top whilst the concrete mix is poured on to the head of the piston, there to be flung outwardly and formed and consolidated into the pipe shell by the packer blades and piston, retracting said blades after the shell formation to within the diameter of the piston, then moving said piston upwardly whilst rotating and whilst feeding a granular lining material on to the head of said piston and finally in returning the rotating piston through the bore with the blades retracted at an axial speed to finally smooth off the lined bore.

3. Concrete pipe making machine comprising a supporting structure, a vertical shaft carried by said structure, a piston on the upper end of said shaft, means for rotating said piston, means for moving said piston carried by said shaft axially through a vertical mould supported by the structure, said axial movement comprising an upward movement from the bottom of the mould to the top for pipe formation and a return downward movement after formation, packer blades on said piston, means for maintaining said blades protuberant of the piston wall when said piston travels from the bottom of the mould upwardly for pipe formation, automatic means retracting said blades to within the piston diameter and operative when said piston rises above the top of the mould, said retracting means maintaining said blades within the piston diameter during the piston return from the top of the mould downwardly, the axial speed on return being a faster rate than the axial pipe forming speed.

4. Concrete pipe making machine comprising a supporting structure, a vertical shaft carried by said structure, a piston on the upper end of said shaft, means for rotating said piston, means for moving said piston and shaft axially through a vertical mould supported by the structure, said axial movement comprising an upward movement from the bottom of the mould to the top for pipe formation and a return downward cleaning and smoothing movement after formation, with the return movement at an axial speed faster than the axial speed during pipe formation, packer elements on said piston, and automatic means retracting the packer elements and operative on the piston rising above the top of the mould.

5. Concrete pipe making machine comprising a supporting structure, a vertical shaft carried by said structure, a piston on the upper end of said shaft, means for rotating said piston, means for moving said piston and shaft axially through a vertical mould supported by the structure, said axial movement comprising an upward movement

from the bottom of the mould to the top for pipe formation and a return downward cleaning and smoothing movement after formation, with the return movement at an axial speed faster than the axial speed during pipe formation, packer elements on said piston, said elements comprising two blades each mounted on a vertical pivot on the piston head and oppositely on a common diameter, a vertical rod concentric within the shaft, a linkage between said rod and the blades, means for moving said rod axially in either direction, said movement in one direction pivoting the blades through the linkage for upward piston movement an amount sufficient for the rear vertical edges of said blades to overhang the piston wall, said movement in the other direction pivoting the blades through the linkage for downward piston movement to retract said rear edges to within the piston diameter.

6. Concrete pipe making machine comprising a supporting structure, a vertical shaft carried by said structure, a piston on the upper end of said shaft, means for rotating said piston, means for moving said piston and shaft axially through a vertical mould supported by the structure, said axial movement comprising an upward movement from the bottom of the mould to the top for pipe formation and a return downward cleaning and smoothing movement after formation, with the return movement at an axial speed faster than the axial speed during pipe formation, packer elements on said piston, said elements comprising two blades each mounted on a vertical pivot on the piston head and oppositely on a common diameter, a vertical rod concentric within the shaft, a linkage between said rod and the blades, means for moving said rod axially in either direction, said movement in one direction pivoting the blades through the linkage for upward piston movement an amount sufficient for the rear vertical edges of said blades to overhang the piston wall, said movement in the other direction pivoting the blades through the linkage for downward piston movement to retract said rear edges to within the piston diameter, the said means for moving the rod comprising a coupling between the lower end of said rod and members mounted on the supporting structure, which members are located to move the rod through the coupling when the piston and shaft assembly reaches its limit of travel in either direction.

7. Concrete pipe making machine comprising a supporting structure, a vertical shaft carried by said structure, a piston on the upper end of said shaft, means for rotating said piston, means for moving said piston and shaft axially through a vertical mould supported by the structure, said axial movement comprising an upward movement from the bottom of the mould to the top for pipe formation and a return downward cleaning and smoothing movement after formation, with the return movement at an axial speed faster than the axial speed during pipe formation, packer elements on said piston, said elements comprising two blades each mounted on a vertical pivot on the piston head and oppositely on a common diameter, a vertical rod concentric within the shaft, a linkage between said rod and the blades, means for moving said rod axially in either direction, said movement in one direction pivoting the blades through the linkage for upward piston movement an amount sufficient for the rear vertical edges of said blades to overhang the piston wall, said movement in the other direction pivoting the blades through the linkage for downward

piston movement to retract said rear edges to within the piston diameter, the said means for moving the rod comprising a pivoted arm carried by the piston and shaft assembly a pivoted coupling between one end of said arm and the lower end of the rod and abutments carried by the supporting structure and spaced apart, one of said abutments engaging the other end of the arm when the piston assembly reaches its limit of travel in either direction to move said rod axially.

8. Concrete pipe making machine comprising a supporting structure, a vertical supporting pillar substantially centrally of said structure, a carrier platform mounted to travel vertically on and supported by said structure, a vertical shaft mounted at its lower end for rotation on said carrier platform, a piston on the upper end of said shaft, retractable packer blade elements on said piston, an electric motor mounted on said carrier platform and coupled to the shaft for the rotation thereof, means for moving the carrier platform vertically on the supporting pillar, means for supporting a mould in axial alignment with the shaft and piston assembly, means for maintaining the packer blade elements protuberant of the piston wall when said piston assembly travels upwardly from the bottom of said mould for pipe formation, means for retracting said blades to within the piston diameter after pipe formation, the means for moving the carrier to return the piston after pipe forming operating to return said piston at a faster axial speed than during pipe formation.

9. Concrete pipe making machine comprising a supporting structure, a vertical supporting pillar substantially centrally of said structure, a carrier platform mounted to travel vertically on and supported by said structure, a vertical shaft mounted at its lower end for rotation on said carrier platform, a piston on the upper end of said shaft, retractable packer blade elements on said piston, an electric motor mounted on said carrier platform and coupled to the shaft for the rotation thereof, means for moving the carrier platform vertically on the supporting pillar, said means comprising a motor driven shaft carried across the top, a counterweighted cable drive from said shaft to the platform, means for supporting a mould in axial alignment with the shaft and piston assembly, means for maintaining the packer blade elements protuberant of the piston wall when said piston assembly travels upwardly from the bottom of said mould for pipe formation, means for retracting said blades to within the piston diameter after pipe formation, the means for moving the carrier to return the piston after pipe forming operation to return said piston at a faster axial speed than during pipe formation.

10. Concrete pipe making machine comprising a supporting structure, a vertical supporting pillar substantially centrally of said structure, a carrier platform mounted to travel vertically on and supported by said structure, a vertical shaft mounted at its lower end for rotation on said carrier platform, a piston on the upper end of said shaft, retractable packer blade elements on said piston, an electric motor mounted on said carrier platform and coupled to the shaft for the rotation thereof, means for moving the carrier platform vertically on the supporting pillar, said means comprising a motor driven shaft carried across the top, a counterweighted cable drive from said shaft to the platform, means for supporting a mould in axial alignment with the

vertical shaft and piston assembly, a vertical rod concentric within the vertical shaft, linkage between said rod and the blades, means for moving said rod axially in either direction, said movement in one direction pivoting the blades through the linkage for upward piston movement an amount sufficient for the rear vertical edges of said blades to overhang the piston wall, said movement in the other direction pivoting the blades through the linkage for downward piston movement to retract said rear edges to within the piston diameter.

11. Concrete pipe forming machine as claimed in claim 9, in which the ends of the motor driven shaft extend one from each side of the framework and each end carries a flanged drum thereon around which a cable is wrapped, one end of each cable being anchored to the framework, the other being connected to the carrier.

12. Concrete pipe forming machine as claimed in claim 10, wherein the motor drives a lay shaft parallel with the cable driving shaft, said lay shaft driving through sprockets and chains two sprockets freely mounted on the cable driving shaft, either of which free sprockets can be connected to the said cable driving shaft by means of a clutch, the sizes of the sprockets being such that for the same motor speed of rotation, the cable driving shaft rotates at a faster rate when the clutch connects up the one sprocket than when said clutch connects up the other sprocket.

13. Concrete pipe forming machine as claimed in claim 12, wherein the direction of rotation of the motor is reversible under the control of switchgear, the reversal of direction automatically actuating means for moving the clutch to change the gear ratio.

14. Concrete pipe forming machine as claimed in claim 13, wherein the means for moving the clutch comprises an arm driven by a friction drive from the lay shaft, which arm is coupled by linkage to the clutch.

15. Concrete pipe making machine comprising a supporting structure, a vertical supporting pillar substantially centrally of said structure, a carrier platform mounted to travel vertically on and supported by said structure, a vertical shaft mounted at its lower end for rotation on said carrier platform, a piston on the upper end of said shaft, retractable packer blade elements on said piston, an electric motor mounted on said carrier platform and coupled to the shaft for the rotation thereof, means for moving the carrier platform vertically on the supporting pillar, means for supporting a mould in axial alignment with the shaft and piston assembly, said means comprising mould locating and retaining members on a horizontal floor plate for the bottom of the mould, and mould locating and retaining members carried by a horizontal tray for the top of the mould, which tray is mounted on the supporting framework by means allowing for the raising and lowering thereof, means for maintaining the packer blade elements protuberant of the piston wall when said piston assembly travels upwardly from the bottom of said mould for pipe formation, means for retracting said blades to within the piston diameter after pipe formation, the means for moving the carrier to return the piston after pipe forming operating to return said piston at a faster axial speed than during pipe formation.

16. Concrete pipe forming machine as claimed in claim 15, wherein the tray is mounted on a linkage connected to a counterbalanced operating

arm, said linkage being constructed so that the tray will move vertically.

17. Concrete pipe forming machine as claimed in claim 16, wherein adjustable stops are provided to maintain the tray against upward movement during pipe forming operations, said stops being mounted and connected to an operating lever whereby they may be swung out of position to allow the tray to rise.
